UNITED STATES PATENT OFFICE.

LORENZO PIGNANI, OF DILLTOWN, PENNSYLVANIA.

TOOL.

1,258,453.

Specification of Letters Patent.

Patented Mar. 5, 1918.

Application filed September 5, 1917. Serial No. 189,806.

To all whom it may concern:

Be it known that I, LORENZO PIGNANI, a subject of the King of Italy, and a resident of Dilltown, in the county of Indiana and State of Pennsylvania, have invented a new and Improved Tool, of which the following is a full, clear, and exact description.

My invention relates to a combination tool and more particularly to a tool in which wrench elements and other tools are coördinated with the handle of a hammer or the like. My present invention resides in a novel wrench assembly for the rear end of the handle of a hammer and consists in the form and arrangement of parts as herein-after explained.

Reference is to be had to the accompanying drawings forming a part of this specification in which similar reference characters indicate corresponding parts in all the views, it being understood that the drawings are merely illustrative of one example of the invention.

Fig. 1 is a side elevation of a hammer equipped with my improved wrench means;

Fig. 2 is an enlarged longitudinal section of the rear portion of the hammer handle and the wrench means;

Fig. 3 is a fragmentary view partly in side elevation and partly in longitudinal section, the view being at right angles to Fig. 2;

Fig. 4 is a rear end view of the improved tool;

Fig. 5 is a perspective view of the rear end of the tool showing a screw driver gripped between the jaws thereof;

Fig. 6 is an end view of the hollow handle with the cap embodying the wrench means removed.

The numeral 10 designates the rear end of a tubular handle of a hammer or similar tool, said tubular handle being adapted to contain miscellaneous tools such, for example, as a combination pliers 11, a double-ended screw-driver blade 12, and a cold chisel 13. The rear end of the tubular handle 10 is in practice provided with a bushing 14 having a polygonal interior to accommodate a polygonal nut of a given size and a removable element 15 conforms to said polygonal bushing and is itself formed with a polygonal interior to fit a nut of smaller size than the bushing 14.

55 A cap designated generally by the numeral 16 and embodying a wrench assembly

is removably fitted on the rear end of the tubular handle 10, the forward end 17 of said cap being interiorly threaded to engage the externally threaded terminal 10^a 60 of the handle. The said cap 16 is provided with wrench jaws 18, the inner ends of which within the cap are formed with lateral flanges 19, said inner flanged ends being received in a T-shaped slot 20 in a traveler 21, 65 housed within the cap. Said traveler is formed with forwardly extending diametrically opposite arms 22 having thread elements 23 at the exterior thereof, and the said threaded arms are adapted to be engaged by a nut or ring 24 turnable on the cap 16, the turning of the nut serving to advance or retract the traveler 21 thereby causing the jaws 18 to be moved outwardly or inwardly to vary the distance therebetween for gripping nuts of different diameters. The arms 22 in the movement of the traveler 21 are accommodated in diametrically opposite slots 25 formed in the rear threaded end 10^a of the handle 10 and in 80 the cap 16. The forward threaded end 17 of the cap 16 is a separate member secured by screws 26 or the like. The jaws 18 extend through oblique slots or openings 27 in the rear portion 30 of the cap 16 and the 85 said rear portion at opposite sides of the slot is formed with lugs 28 received in recesses 29 in the opposite side faces of the jaws 18, the arrangement serving to steady the jaws and make the same rigid in any 90 given adjustment. The rear portion 30 is a separate cap piece secured by a screw 31 or the like to the tubular body 32 of the cap.

In addition to the function of the jaws 18 as wrench jaws, they may be utilized for 95 gripping the screw driver blade 12 as indicated in Fig. 5, or for gripping the cold chisel 13, or similar tool.

Those portions of the parallel slots 25 that extend into the rear end 10^a of the handle are covered or bridged by the polygonal element 15 so that the arms 22 may pass beneath said element when moving toward the extreme forward position.

It is to be noted also that the screw 31 extends into the path of the traveler 21 to limit the rearward movement of the traveler.

In Fig. 1 the numeral 33 indicates another form of wrench which is removably received longitudinally in the forward end 10^b of the 110 shank of the hammer and in the head 34 thereof, said wrench 33 being adapted to be

locked in position by a nut or ring 35 as described in a separate application filed by me concurrently herewith.

I wish to state in conclusion that although the illustrated example constitutes a practical embodiment of my invention, I do not limit myself strictly to the mechanical details herein illustrated, since manifestly the same can be considerably varied without departure from the spirit of the invention as defined in the appended claims.

Having thus described my invention, I claim as new, and desire to secure by Letters Patent:

1. In a tool of the class described, a tubular handle; a cap comprising a tubular body, the annular inner end thereof having threaded engagement with the tubular handle, a separate rear end member on said tubular body and forming a closure therefor, said closure having oblique slots, a ring held between the said front and rear members and formed with internal threads, a screw extending transversely through the said rear member and through the tubular body to project at the interior of the latter, jaws movable in the oblique slots and extending

to the interior of the tubular body, and a traveler within said tubular body and engaging the inner ends of the jaws, said traveler having arms thereon formed with external threads engaged by the threads of the said ring, the tubular body having slots in which the said arms of the traveler may move in response to the turning of the ring, and said screw constituting a stop limiting the outward movement of the traveler.

2. A tool of the class described, including a tubular handle, a bushing in the rear end of the handle, a cap on said handle, there being parallel internal slots extending in the said cap and into the end of the handle, the slots in the handle being radially outward from the said bushing, a member forming a closure for the said cap, said member having oblique slots therein, jaws slidable in said oblique slots and extending within the cap, a traveler engaging the jaws at their inner ends, arms on the traveler movable in the said parallel slots, and a ring revolvable on the cap and formed with internal threads engaging the arms of the traveler.

LORENZO PIGNANI.
